UNITED STATES PATENT OFFICE.

JOHN PAYNE, OF NEW HAMBURG, ONTARIO, CANADA.

SASH-FASTENER.

SPECIFICATION forming part of Letters Patent No. 230,434, dated July 27, 1880.

Application filed May 1, 1880. (Model.) Patented in Canada March 30, 1880.

To all whom it may concern:

Be it known that I, JOHN PAYNE, of New Hamburg, in the county of Waterloo, in the Province of Ontario, Canada, have invented 5 certain new and useful Improvements in Sash-Fasteners; and I do hereby declare that the following is a full, clear, and exact description of the same.

This invention relates to an improvement in 10 sash-fasteners of that class having a pinion-wheel engaging with a rack-bar on the sash or the window-casing; and the object of the invention is to lock the pinion by two over-turning pawls, whereby the pinion revolves 15 past one of them in one direction and not in the other to lock the sash when open or closed, or to arrest it from falling when partly raised; and my invention consists of an open cast-metal frame having two sides, between which 20 the pinion-wheel and pawls are journaled on holding-screws, which secure said frame in position. The two pawls are hung at the upper extremity of the frame to gravitate in engagement with the pinion, said pawls having a turn-over movement one upon the other, to cause 25 one or both pawls to engage with the pinion to lock the sash, as above described.

Figure 1 is a front elevation of the upper sash, with fastener of modified construction. 30 Fig. 2 is a side elevation of the lower sash with my improved fastener. Figs. 3 and 4 are side views of the fasteners shown in Figs. 1 and 2, respectively.

A is the sash; B, a rack-bar secured to the 35 sash, as in Fig. 2, or window-casing, as shown in Fig. 1.

C is an open metal frame, having two side bars connected by an intervening bar or bars, whereby the sides are kept rigidly apart and 40 to allow the frame to be cast integrally.

D is a pinion-wheel journaled between the sides of the frame A upon a holding-screw passing through the sides of the frame A, and which screw also serves to fix the frame to the 45 sash or casing in such a position that the pinion will engage with the rack-bar B.

F F are two pawls hung on a pin or holding-screw passing through the upper extremity of the metal frame C into the window-casing.

Both pawls are halved at the pivot-hole, where- 50 by a shoulder is formed on the extremity which engages with the pinion D. The upper pawl, (shown in Fig. 2,) when in engagement with the pinion, prevents the sash being lifted, and the lower pawl sustains the sash from falling. 55 When both pawls engage with the pinion the sash is held from movement either up or down when partly open.

When the upper pawl in Fig. 2 is overturned outwardly from the sash to lie on the back of 60 the lower pawl, so as to be out of engagement with the pinion, the pinion will revolve past the lower pawl when raising the sash, but will be arrested by it when falling, and thus sus- 65 tain the sash at any desired height.

When both pawls are engaged with the pinion, as shown in Fig. 2, the sash will be locked 70 when open, so that it cannot be moved either up or down, and in like manner the sash will be locked from rising when closed by the en- 75 gagement of the lower pawl, which must be overturned from engagement when the sash is being lowered. The pinion will then revolve past the upper pawl on the downward move- 75 ment of the sash, and when closed is prevented from rising by the upper pawl taking effect.

The engagement of both pawls with the pinion is effected by gravitation, and each pawl has a turn-over disengagement movement upon 80 the other than in engagement with the pinion, whereby, when such change of engagement occurs, the pinion revolves past the one in engagement in one direction, but not in the other.

The pawls are provided with a projection, F', to facilitate manipulation by the fingers, 85 as above described.

In Figs. 1 and 3 I show, as a modification, a pawl corresponding to the two pawls F F if cast integrally back to back, with a turn-over adjustment, whereby the sash can be arrested 90 from falling or from being raised when open; but such pawl will not lock the sash immova- bly when open.

I am aware that it is not new to place the pinion on the sash and rack on the window- 95 casing, and vice versa, and I do not broadly claim such arrangement as my invention.

I claim as my invention—

The combination, with a rack-bar, B, of a sash-fastener composed of the open frame C, pinion D, and two pawls, F F, hung at the upper extremity of the frame to gravitate in engagement with the pinion, each pawl having a turn-over disengagement from the pinion, one upon the other, to allow the pinion to revolve past the pawl in engagement in one direction,

but not in the other, whereby the sash is immovably fixed when partly open, or arrested from falling, or locked when closed by the adjustment of the pawls, as set forth.

JOHN PAYNE.
